UNITED STATES PATENT OFFICE.

MAX WOHLGEMUTH, OF NEW YORK, N. Y., ASSIGNOR TO NEVASLIP UNDERGARMENT CORPORATION, A CORPORATION OF NEW YORK.

GARMENT AND SUPPORTER THEREFOR.

Application filed January 13, 1926. Serial No. 81,056.

This invention relates to garments and means for supporting the same upon the body of the wearer, and is of particular utility when embodied in the construction of such garments as gowns, dresses, bathing-suits, costume-slips, vests, chemises, under-suits, undershirts, brassières, aprons, and other articles of underwear or outer wear made of cotton, wool, slik, artificial silk or any suitable material, and I contemplate the use of the invention for any garment to which it may be applied with advantage.

More particularly, the invention is applicable to garments having flexible shoulder straps serving to support the garment, and the object of the invention is to provide means for preventing the shoulder straps from slipping down from the shoulder of the wearer on either side of the body, a tendency to which such straps are constantly subject in the absence of such retaining means as form the object of this invention.

Another object of the invention is to provide adjustable, flexible retaining devices for the above purpose which may form an integral part of the garment structure, or may be formed separately and applied by the wearer as required.

In carrying the invention into effect, I prefer to utilize flexible tapes or ribbons of fabric which may be of elastic or non-elastic material, and these tapes may be secured to the straps by stitching, or by adjustable clips, and may be similarly secured to the body of the garment either at the front or the back thereof, and which preferably will extend diagonally from an intermediate portion of each strap toward the central portion of the upper margin of the garment, passing through suitable apertures in said margin and extending to a convenient point at the middle of the upper margin where the loose ends of the flexible tapes may be brought out conveniently in position to be tied together adjustably in a bowknot.

These and other features of the invention are illustrated and described fully in the accompanying drawings and specification and are pointed out in the claims.

In the drawings,

Figure 1 is a front elevation of a garment provided with an attachment in which the invention is embodied.

Fig. 2 is a fragmentary detail view on a larger scale of the region of the tie.

Fig. 3 is a view similar to Fig. 2, of a modification of the attachment shown in Figs. 1 and 2.

In the illustrated embodiment, referring to Fig. 1, the reference numeral 1 designates the body of a garment, such as a shirt having conventional shoulder straps 2 of ribbon or similar flexible material, adapted to extend in an upright position from front to rear over the shoulders of the wearer. In pursuance of the invention, I have shown at 3 and 4, retaining members of flexible material, such as ribbon or tape, formed of elastic or non-elastic material as may be preferred, these retaining members being shown as stitched at 5 to intermediate portions of the straps 2 respectively, and extending diagonally therefrom toward the upper margin 6 of the garment, where the loose ends of the members 3 and 4 are inserted through suitable apertures 7 in a transverse pocket 8, such as that usually found in such garments for the purpose of enclosing a shirr-string 9 of ribbon or the like, the ends of which pass out through an aperture 10 at the middle of the front portion of the garment, being there tied in a bowknot 11.

In Figs. 1 and 2, the ends 12 of the retaining members are shown as brought out through the same aperture and tied in a separate bowknot 13, so that by drawing them more or less tightly the retaining members will serve adjustably to accommodate themselves to the size of the body of the wearer.

In Fig. 3, I have shown a modification in which the loose ends 12 are brought out through separate holes 14 on each side of the central hole 10, so that they will be separate from the bowknot 11 and may be tied in a knot which will not interfere with the knot 11.

In each of the forms illustrated, the retaining member constitutes an effective device for holding the shoulder strap in its desired position, the retaining member being readily adjustable to secure its intended effect.

Having illustrated and described my invention thus fully, it is to be understood that I do not limit myself to any specific

material or structural form of the retaining member, nor in general otherwise than as set forth in the claims read in connection with this specification.

5 What I claim as new and desire to secure by Letters Patent is:—

1. A garment of the class described, comprising a body portion, flexible supporting straps therefor adapted to extend in an upright position over the shoulders of the wearer, and flexible adjustable retaining members for said straps, said retaining members being attached to said straps at an intermediate portion thereof respectively, each 15 retaining member passing from its said point of attachment diagonally downward to a point of connection with said body portion, and having free ends each extending from the connection with said body portion, the 20 free ends being adapted to be tied together adjustably across the body of the wearer.

2. A garment of the class described, comprising a body portion, flexible supporting straps therefor adapted to extend in an upright position over the shoulders of the wearer, and flexible adjustable retaining members for said straps, said retaining members being attached to said straps at an intermediate portion thereof respectively and

adapted to be tied together adjustably across 30 the body of the wearer, passing diagonally from their respective points of attachment to said straps downward toward spaced points of connection with said body portion and thence passing through a pocket in the 35 upper margin of said body portion to a central apertured portion, where they emerge in juxtaposition to each other.

3. A garment of the class described, comprising a body portion, flexible supporting 40 straps therefor adapted to extend in an upright position over the shoulders of the wearer, and flexible adjustable retaining members for said straps, said retaining members being attached to said straps at an intermediate portion thereof respectively and 45 adapted to be tied together adjustably across the body of the wearer, passing diagonally from their respective points of attachment to said straps downward toward spaced 50 points of connection with said body portion and thence passing through a pocket in the upper margin of said body portion to a plurality of central apertures, where they 55 emerge in juxtaposition to each other.

In testimony whereof, I have signed this specification.

MAX WOHLGEMUTH.
